TAKE-UP

Charles C. Jessen, Miami, Fla., assignor to
Jacquard Knitting Machine Co., Inc.,
Philadelphia, Pa., a corporation of New
York

Application January 8, 1947, Serial No. 720,852

3 Claims. (Cl. 66—149)

1

My invention relates to cloth take-ups for drawing cloth from the point of its fabrication (whatever may be the means of fabrication), and maintaining it under tension at that point. The feed is step by step, the step length being variable under control of, and corresponding more or less to, the rate of cloth production. Ordinarily in this type of take-up, successive steps or impulse increments are passed on to the rotary member or members of the take-up or that one of those members that is power driven. The series of steps or jerks to which the cloth is thus subjected is objectional in some instances; for example in warp knitting machines it tends to cause objectionable streaking of the cloth.

My invention tends to obviate this effect by interposing between a rotary member pulling the cloth and the step by step drawing mechanism which rotates this take-up member, mechanism to receive and store energy of the rotation-producing impulses and transfer such energy to the rotary take-up member at, at least, a more nearly constant rate. This reduces the variations in the momentary speed of rotation of the take-up, that is to say, those variations caused by a step by step nature of the driving mechanism as distinguished from those long range variations in speed to which the take-up may be subjected by reason of or to compensate for, say, the accumulation of cloth on a beam. As will more fully appear in the detailed description, the energy receiving and storing mechanism spreads the increments over greater time intervals, thus minimizing or softening them and tending to eliminate or render negligible the otherwise objectionable jerks on the cloth.

Referring to the drawings in which is illustrated an otherwise known type of cloth take-up to which my invention has been applied and in which it is exemplified:

Fig. 1 is an end elevation, partly in vertical section, of the cloth winding mechanism;

Fig. 2 is a plan view of the same mechanism, parts being broken away and in section; and

Fig. 3 is a representative showing of the operation and also a showing of the ideally preferred operation.

In the device illustrated the cloth take-up mechanism includes a step by step drive, a step-length control responsive to differences between the rate of cloth production and the rate of winding the cloth on the beam, and spring means modifying said drive before its application to the cloth beam. This mechanism, including cloth beam 1 with its shaft extensions 2, 3, is assembled

2

on bracket plates 4, 5 of the main frame; the cloth beam may be carried demountably, say in some customary manner. Ratchet wheel 6, fixed to stub shaft 7 which is rotatable in bearings in plate 4, is driven by pawl 8 hinged at 10 on pawl carrier 9 which is mounted for oscillation on shaft 7; the pawl is urged about pin 10 of the carrier by spring 11 into driving relation with the ratchet teeth. A power shaft 12, by gears 13, 14, wrist pin 15 and connecting rod 16 to pin 17 through the knuckle of the carrier, oscillates the pawl carrier and its pawl 8 constantly. Holding means, as the pawl 18, urged about sleeved pin 19 projecting inward from the plate 4 by spring 20 into holding contact with the ratchet, prevents reverse movement. Gear 21 fixed to shaft 7 and meshing with gear 22 loose on cloth beam shaft 2, imparts to the latter gear the step by step driving impulses developed by the pawl and ratchet, and the energy of which, in a manner hereinafter explained, is modified and transferred to the cloth beam itself.

The control means for altering the effective throw of the pawl to insure due co-ordination with the rate of cloth production, may be the known mechanism illustrated. In this device a hub 23, free for oscillation on shaft 7, has a radial extension from which a shield 24 projects laterally over the teeth of the ratchet 6, and to a variable extent between them and the path of the pawl 8. This shield covers a greater or less number of teeth depending on its angular position. It thus determines the effective throw of pawl 8. The angular location of the shield is determined and varied by the position of the dancer roll 25 which is trunnioned in arms 26, 27 fixed to shaft 28 and from which arms weights 29 may be hung as indicated. A third arm 30 fixed to shaft 28 has lugs 31 and 32 coacting with stop pin 33 to limit the range of motion in extreme cases. Arm 26 terminates in gear segment 34 meshing with gear segment 35 on hub 23 of the shield 24. The dancer roll rests in and is suspended by a bight of the cloth between the point of cloth fabrication f and the beam 1; in the present instance in a bight between the point of fabrication f and the idler roller 36 provided to direct the cloth to the beam along a desired path. The weight of the dancer roll 25, plus any weights at 29, determines the tension of the cloth at the fabrication point f; by adding or subtracting weights at 29, this tension can be changed at will. Whenever the average peripheral speed of the roll of cloth on beam 1 exceeds the rate of cloth production at f, the bight short-

3

ens and raises the dancer roll 25, and this moves shield 24 to cover more ratchet teeth from the pawl so that the effective throw of the pawl is shortened, thus reducing the rate of cloth wind-up on the beam. Contrariwise, whenever the wind-up or average peripheral speed of the cloth roll becomes less than the rate of fabric production, the dancer roll falls and shifts the shield to uncover more teeth to pawl action, the effective throw of the pawl is lengthened and the wind-up rate is increased. Over considerable periods of time therefore the rate of winding of the cloth on the beam is equalized to the rate of cloth production. The real throw of the pawl, both forward and back, remains unchanged, of course.

To modify and transfer the (initially step by step) drive to the beam itself, at least two spaced opposed abutments 37, 38 (and preferably two or more such pairs in substantially equiangular placements about an axis in the drive, e. g. about the beam axis), are provided. The abutment or abutments 37 are fixed to a step by step driven member; in the present instance the gear 22 or to a plate 39 attached to this gear. The abutment or abutments 38 are attached to the cloth beam 1 in a manner to rotate the beam; for example to more or less radially extending arms 40, 41 keyed to the cloth beam shaft 2. A spring 42 is provided between the abutments of each pair to transfer the driving energy from 37 to 38. Each spring may be seated in recessed faces as shown, and bolts 43 with nuts 44 and lock nuts 45 may be used to anchor the springs in place, to prevent undue separation of each abutment 38 from its companion abutment 37 by the thrust of the spring or springs or otherwise, and to tension the springs if desired.

The tension under which the spring or springs 42 are held by the bolt or bolts 43 is such that any advance of the abutment or abutments 37 enables the spring or springs to turn the beam 1 (in a direction to wind on further cloth). Or they may be so constructed that a few preliminary step advances by the abutment or abutments 37 will, and are needed to, compress the spring or springs sufficiently to move the beam. Further, the spring or springs 42 are so made (i. e. have such characteristics) that once a step advance of an abutment or abutments 37 causes or permits the spring or springs 42 to turn the beam, the spring or springs continue to turn the beam for a time after that advance of 37 ceases; namely, for such a time thereafter that the total period during which the beam turns, consequent on that advance of the abutment or abutments 37, is greater than the period during which the latter abutment or abutments 37 make the respective advance. Consequently the instantaneous speed of the beam is, as it were, always less than the speed of the abutment or abutments 37 while the latter are in motion, and the spring or springs 42, by absorbing energy from the abutment or abutments 37 rapidly, and applying this energy to the beam more slowly, transforms the jerky relatively high-speed-short-period driving impulses of the pawl 8 and abutment or abutments 37, into relatively low-speed-long-continued, and accordingly smoother, turnings of the beam. Speaking generally, the longer the spring or springs 42 keep the drum turning after each advance by the abutment or abutments 37, the better. Preferably springs 42 are used which have such characteristics that once started the

4

turning of the beam does not stop so long as power is supplied to the pawl.

The ideal of this latter action, after the take-up mechanism has reached a condition of stable operation, is illustrated in the diagram of Fig. 3. In this diagram time is measured from *a* to *g*, and the diagram indicates, by their displacements from the line *a* to *g*, positions of two abutments 37 and 38 of a pair at the ends of successive periods during three consecutive cycles of the operations. It shows also the action of a spring 42 between such abutments. At time *a* the pawl 8 begins an effective stroke and accordingly the abutment 37 begins to advance. During the interval *a* to *b*, the abutment 37 advances to its position at *b* and, the pawl 8 having reached the end of its effective stroke, comes to rest. In making this advance the abutment 37 increases the compression of its spring 42. Also during this interval *a* to *b* the compression in spring 42 advances its abutment 38 from its position at *a* to its position at *b*, and accordingly turns the beam 1 a corresponding distance. While abutment 37 comes to rest at time *b*, the energy stored in spring 42 at this time, in the form of compression, continues the advance of the abutment 38 and the turning of the cloth beam 1, and this advance and turning continues to the time *c* when the pawl 8 begins its next effective stroke and accordingly when the abutment 37 starts to advance the next step; preferably the compression in 42 is such (and its limiting bolt 43 is of such length) that the spring is capable of continuing to advance the abutment 38 somewhat beyond the time *c* even if abutment 37 should not advance again; this prevents the beam stopping even momentarily at time *c* and at corresponding times in other cycles. At time *c* therefore the cycle is completed and another begins, the abutment 37 now advancing another step during the interval *c* to *d* (a step like that taken in the interval *a* to *b* if the dancer roll 25 has not moved up or down and thereby changed the length of the effective stroke of the pawl 8), and then again coming to rest, and the spring 42 advancing the abutment 38 and turning the beam 1 from time *c* to time *e*. This completes a second cycle, and the subsequent cycles will be like these two described except as the rising and falling of the dancer roll 25 may lengthen and shorten the effective strokes of the pawl 8, and accordingly lengthen or shorten such periods of time as *a* to *b* and *c* to *d*, and correspondingly change the extent of the abutment movements and thereby the rate of turning of the cloth beam. The slope of the broken line drawn through the various positions of the abutment 38 in Fig. 3 indicates the momentary average speed of advance of this abutment and the average peripheral speed of the roll of cloth on the beam, and also that I prefer to rotate the roll of cloth constantly, and at a constant peripheral speed, so far as it is reasonably possible to approximate these.

As before indicated however, Fig. 3, as described above, illustrates the ideal mode of operation with my invention, or that mode of operation which ordinarily I approach so far as may be reasonably convenient, in any instance, or so far as may be necessary to eliminate or to reduce to a desired extent the irregularities in the cloth that otherwise may occur because of the step by step driving action of the pawl 8. In other words, my invention is not limited to this described operation. For example, instead of the abutment or abutments 38 moving momentarily at a uni-

form speed as suggested in Fig. 3, such a spring or springs 42 may be used that the speed of the abutment or abutments 38 is relatively low at time *c*, then increases more or less gradually to about time *d*, and then fall again, more or less gradually, to time *c*, and this speed vary similarly during the other cycles. As another example, such a spring or springs 42 may be used that the abutment or abutments 38 come to rest somewhere between time *b* and time *c*, and start again somewhere between time *c* and time *d*, and similarly move intermittently during the other cycles; in any such case where the length of each period of movement of the abutment or abutments 38 exceeds the length of the preceding period of movement of the abutment or abutments 37 (e. g. exceeds the period from *c* to *d*), some of the advantages of the invention are achieved. The maximum advantage of the invention is achieved when the momentary speed of the abutment or abutments 38 is constant—that is to say, is uniform except as it may need to vary, slowly, to compensate for the growth of the diameter of the roll of cloth on the beam as more and more cloth is wound on it.

In general it will be understood that my invention is not limited to the details of construction and operation described above and shown in the drawings except as appears hereafter in the claims.

I claim:

1. A cloth take-up including power driven step by step driving mechanism, a cloth beam, at least one pair of abutments disposed in substantially the same plane and revolvable around an axis substantially at right angles to said plane, of which pair one abutment is connected to said beam to rotate the beam and the other abutment

is connected to said driving mechanism to be driven, step by step, by said mechanism, and a spring interposed between the abutments of each pair to receive and store energy of the beam-rotating impulses of the step by step driving mechanism and transfer such energy to the cloth beam.

2. The subject matter of claim 1, characterized by the fact that a plurality of pairs of said abutments, with interposed springs, are provided, and said pairs are distributed substantially equiangularly about an axis of the driving mechanism.

3. In a cloth take-up, a cloth beam, a pawl and ratchet mechanism to drive the beam, at least two abutments distributed substantially equiangularly about the axis of the cloth beam, means through which said pawl and ratchet mechanism can rotate said abutments around said axis, a corresponding number of cooperating abutments fixed to and around the axis of said beam, and a spring between the members of each pair of said abutments to transmit motion of the first of said abutments to the beam.

CHARLES C. JESSEN.
